UNITED STATES PATENT OFFICE

RAYMOND W. FRAWLEY AND GEORGE C. BRUNER, OF BIRMINGHAM, ALABAMA

TIE PLATE

Application filed July 1, 1930. Serial No. 465,206.

This invention relates to improvements in tie plates having the usual top rail seat portion and rail abutment and provided with a novel bottom or tie engaging portion comprising a plurality of blunt rounded ribs with shallow arcuate grooves between them, which grooves are bridged by transversely extending pointed ribs. The pointed ribs preferably being located under the rail seat and extending transversely of the plate or in the direction of the length of the rail adapted to be supported on the tie plate. Preferably, the grooves separating the rounded ribs taper downwardly and outwardly at their ends and the arrangement is such that the lower extremities of the rounded ribs and the pointed ribs lie in the same plane. The invention further consists in various features of structure and arrangement described, illustrated and pointed out with particularity in the appended claims.

A preferred embodiment of the invention is illustrated in the accompanying drawings, in which:

Fig. 1 is a top plan view showing the rail seat portion of the tie plate;

Fig. 2 is an inverted plan showing the tie engaging portion of the plate;

Fig. 3 is a section on line 3-3 of Fig. 2;

Fig. 4 is a section on line 4-4 of Fig. 3.

Referring in detail to the drawings, the upper surface of the tie plate is provided with a rail seat portion 10 and a transversely extending rail abutment 12.

The under surface or tie engaging portion of the tie plate includes a plurality of longitudinally extending ribs 14 which as clearly shown in Fig. 4 are rounded at 16 at their lower extremities. The ribs 14 are separated by shallow arcuate grooved portions 18 which at their ends terminate in downwardly and outwardly extending flat sloping portions 20. At their extremities, these sloping portions merge into the flat surfaces 22 which extend transversely at each end of the tie plate.

Bridging the grooves 18, we preferably provide a plurality of pointed ribs 24 and 26. There is a separate rib 24 bridging each

groove near one end of the tie plate and there is a separate rib 26 bridging each groove at a location near the other end of the tie plate. The pointed ribs 24 and 26 jointly form a parallel row of ribs which extend transversely below the rail seat 10.

The construction defined is an improvement over tie plates heretofore available. The rounded ribs have less tendency to split the tie than sharp ribs provided on tie plates of the prior art. The rounded ribs are also desirable from the standpoint of manufacture because the tie plates of this character are preferably made of rolled metal. By

providing blunt rounded ribs, certain rolling difficulties are avoided because there is a better distribution of rolling stresses providing a construction in which the longitudinally extending ribs have a relatively great mass. This is of importance especially where the ribs extend transversely to the direction of rolling. There is less difficulty in rolling the sharp ribs 24 because the rolls for forming these have only to be provided

with circumferentially extending V-shaped grooves.

By forming the grooves 18 with the inclined portions 20 which merge into the surfaces 22 of the extremities of the plate, it will be understood that the chambers formed by the grooves will be closed at the ends so as to preclude the free entrance of water or other foreign matter under the tie plate.

It is also an advantageous feature of our invention to provide a tie bearing surface in which the extremities of all of the ribs as well as the end portions 22-22, lie in the same plane. This gives an even bearing surface so that when the tie plate is initially installed, the load is distributed substantially uniformly.

The rounded bearing surfaces 16 of the ribs 14 are advantageous as they avoid cutting the fibers of the tie apart as the sharp ribs of prior tie plates do. The rounded ribs gradually compress the fibers of the tie downwardly as well as sidewise so that the load transmitted by the tie plate is balanced on the tie. The yielding of the wood fibers provides complimentary grooves which in-

terlock with the rounded ribs. This gives an increased or extended bearing surface for the underside of the tie plate and also prevents the latter from slipping crosswise of the tie.

The intermediate pointed ribs 24 and 26 and the rows of ribs at each end of the tie plate which are formed by the sloping portions 29, the flat surfaces 22 and the ends 10 of the plate stiffen and brace the plate in a direction parallel to the length of the rail or the rail abutment. These ribs 24 and 26 and the rib-like portions 22 sink into the tie a sufficient depth to prevent the tie plate from slipping lengthwise of the tie. The configuration of the tie engaging bottom portion of the plate as shown and described is advantageous because of the provision of a plurality of recessed areas into which the 20 wood fibers near the surface of the tie are forced by compression in four directions, but in such manner as to not disturb the fibers of the wood in the plane of shearing at the bottom of the tie plate.

While the tie plate illustrated is provided with a canted rail seat 10, it will of course be understood that the tie plate may have a flat seat substantially parallel to the undersurface thereof or in some instances 30 the rail engaging seat may be cambered.

While we have described quite specifically the tie plate illustrated it is to be understood that various equivalents may be substituted without departure from the invention as defined with particularity in the appended claims.

What we claim is:

1. A tie plate comprising a top portion 40 having a rail seat and a rail abutment, a bottom tie engaging portion having a plurality of blunt rounded ribs with shallow arcuate grooves between them and transversely extending pointed ribs bridging said 45 grooves.

2. A tie plate comprising a top portion having a rail seat and a rail abutment, a tie engaging bottom portion having longitudinally extending rounded ribs with shallow arcuate grooves between them, said 50 grooves terminating at their ends in downwardly and outwardly extending surfaces, and pointed ribs parallel to the rail abutment extending transversely across said 55 grooves, the lower extremities of the rounded ribs and the pointed ribs lying in substantially the same plane.

3. A tie plate substantially as described 60 comprising a top rail seat portion having a transversely extending rail abutment, a tie 65 engaging portion comprising a plurality of parallel longitudinally extending ribs whose lower extremities are rounded, said rounded ribs being separated by shallow arcuate 85 grooves, which terminate at each end of the

tie plate in flat downwardly sloping surfaces.

4. A tie plate substantially as described comprising a top rail seat portion having a transversely extending rail abutment, a tie 70 engaging portion comprising a plurality of parallel longitudinally extending ribs whose lower extremities are rounded, said rounded ribs being separated by shallow arcuate grooves, which terminate at each end of the 75 tie plate in flat downwardly sloping surfaces and a plurality of transversely extending ribs bridging said grooves, said latter ribs being disposed below the rail seat portion substantially parallel to said rail abutment.

In witness whereof, we have hereunto signed our names.

RAYMOND W. FRAWLEY.
GEORGE C. BRUNER.
